UNITED STATES PATENT OFFICE.

ALEXANDER M. ALEXANDER, OF BEVERLY, MASSACHUSETTS, ASSIGNOR TO UNITED SHOE MACHINERY COMPANY, OF PATERSON, NEW JERSEY, A CORPORATION OF NEW JERSEY.

SKIVING-MACHINE.

1,200,066.

Specification of Letters Patent.

Patented Oct. 3, 1916.

Application filed December 31, 1914. Serial No. 879,904.

To all whom it may concern:

Be it known that I, ALEXANDER M. ALEXANDER, a citizen of the United States, residing at Beverly, in the county of Essex 5 and State of Massachusetts, have invented certain new and useful Improvements in Skiving-Machines; and I do hereby declare the following to be a full, clear, and exact 10 description of the invention, such as will enable others skilled in the art to which it appertains to make and use the same.

The present invention relates to skiving machines and more particularly to skiving machines having a rotary cylindrical skiving 15 knife for operating upon leather or analogous materials.

One object of the present invention is to so improve the construction and operation of machines of this character that pieces of 20 leather may be split throughout their width or beveled upon the edge with equal facility.

A further object of the invention is to provide a machine in which the knife and feeding mechanism are arranged relative 25 to one another so that the work may be fed freely past the cutting edge of the knife and the waste material ejected without liability of clogging the moving parts of the machine.

With the above objects in view the several 30 features of the invention consist in certain novel features of construction, combinations and arrangements of parts hereinafter described and claimed, the advantages of 35 which will be obvious to those skilled in the art from the following description.

In the accompanying drawings illustrating 40 the preferred form of the invention; Figure 1 represents a front elevation partly in section of a machine embodying the several features of the invention; Fig. 2 is a top plan view of the machine shown in Fig. 1; Fig. 3 is an end elevation of the machine shown in Fig. 1; Fig. 4 is a detail 45 showing the mechanism for clamping the knife blade to the holder; and Fig. 5 is a detail illustrating partially diagrammatic the cutting edge of the knife and the co-operating work feeding mechanism to show 50 the manner in which the work is fed by the cutting edge.

It will be obvious to those skilled in the art that when using this machine for splitting leather the work must be gripped firmly over a considerable portion of its area 55 to prevent the action of the knife edge from diverting it from its path of feed. In employing the machine for beveling the edge, however, it is advisable to grip only a small portion of the work immediately in advance 60 of the cutting edge to permit the work to be turned as desired when feeding it to the knife-edge. In the present invention feeding mechanism is employed which is arranged to grip the work for a greater or less 65 distance in advance of the knife edge in order to accommodate the machine for operation for either skiving or splitting. The machine shown in the illustrated embodiment of the invention comprises a casing 1 70 having a rotary skiving knife indicated generally at 2 and journaled in a stationary bearing 3 supported by the casing. The work is fed to the knife by co-operating feeding members indicated respectively at 75 4 and 5 and engaging with opposite faces of the leather. These feeding members are provided with feeding surfaces which may move either in parallel paths or in paths inclined to one another in order to vary the 80 area of the work engaged by the feeding surfaces. To this end the feeding members comprise two co-operating feed belts 6 and 7 which may be adjusted to have a substantial 85 area of contact between the feeding surfaces and the work, as shown clearly in Fig. 1, or may be adjusted so that one feed surface engages the work with substantially a line contact immediately in front of the cutting edge. The feed belt 6 engages with 90 the upper surface of the work and passes over rolls 9 and 10 at its opposite ends which are supported by an overhanging head 15. The roll 10 is journaled upon the lower end of a head 13 and is operatively 95 connected to the roll through an arm 12 fulcrumed concentrically with the roll.

The position of the two rolls and feed belt is determined by a curved arm 14 connecting the end of the arm 12 with a projecting arm 100 formed upon the head 13 and provided with a slot 16 which receives a clamping stud 18

threadedly connected to the head 13. With this construction, by loosening the clamping stud the arm 12 may be adjusted about the axis of the roll 9 to position the feed belt 6 either parallel or at an inclination to the coöperating feed belt 7, thus varying the area of the work which is engaged by the feeding members. The belt 6 is normally retained in the position shown in Fig. 1 in which the entire working portion of the belt engages with the work by a tension spring 20 which connects the head 15 with an arm 21 projecting rearwardly from the arm 12. The rolls 9 and 10 and the belt 6 are curved transversely to conform substantially to the curvature of the knife, as shown clearly in Figs. 1 and 3, and the head 13 is provided with a transverse adjustment relative to the supporting head 15 in order to position the presser belt relative to the knife as is usual in machines of this type. A vertical adjustment of the supporting rolls and belt is obtained in the usual manner through the provision of an adjusting screw 22 threadedly supported in the head 15. The work is retained in engagement with the presser belt by a feed belt 7 engaging with the under side of the work and supported at its opposite ends upon rolls 23 and 24 which are journaled upon a supporting arm 26 fulcrumed at 27. The feed belt is yieldingly retained in the position shown in Fig. 1 by a spring 30 interposed between the machine frame and a depending leg 29 which is recessed to receive the end of the spring. The normal position of the feed belt is determined by an adjustable stop member 31 which engages with a coöperating projection 32 formed upon the depending leg 29 to limit the upward movement of the feed belt in the usual manner. The upper or presser belt, as it may be termed, serves as a presser member to gage the movements of the work relative to the knife, whereas the lower or feed belt maintains the work in engagement with the presser belt and feeds it against the cutting edge. To this end mechanism is provided for driving the roll 23 from a shaft 34. It will be noted from an inspection of the drawings that the roll 23 is larger than the roll 24 and has sufficient peripheral area to properly engage with and drive the belt. The roll is connected to the countershaft 34 through intermeshing worm gearing indicated at 35 and a short traverse shaft 36 connecting the worm gears and roll to a pair of universal joints indicated respectively at 37 and 38. The shaft 34 is connected to the main drive shaft 40 through a connecting belt 41 and drive pulleys 42 and 43, respectively.

In machines of this type it is customary to form the cutting edge by beveling the outer surface of the knife and with this construction considerable difficulty may be experi-

enced in obtaining sufficient clearance between the surface of the knife and the surface of the presser belt or other member which engages with the work above the knife. To this end the present invention contemplates supporting the knife at an inclination to the direction of feed of the work in such a manner that the beveled outer surface of the knife extends in a direction substantially parallel to the direction of feed at a point where the knife engages with the work. In the illustrated embodiment of the invention the knife is journaled obliquely in a stationary bearing 3 and projects upwardly into a position in which the operating portion of the cutting edge is located between and in close proximity to the feeding members, the arrangement enabling sufficient clearance to be obtained for the passage of the work between the knife and presser belt, as shown clearly in Fig. 5.

The rotary skiving knife employed in the present invention comprises a knife blade which is clamped rigidly to an internal holder to enable a true cutting edge to be obtained and which may be readily adjusted to permanently maintain the cutting edge in operative relation to the feeding members as the cutting edge is ground away. To this end a knife blade 45 is supported upon an internal holder 46 and is clamped to the holder by a split clamping ring 47, the opposite ends of which are drawn together to contract the ring by pivoted actuating levers 49 engaged by a tapered head 50. As shown clearly in Fig. 4, by moving the head 50 in a lengthwise direction the levers 49 are rocked to draw the opposite ends of the clamping ring 47 together. This movement of the tapered head is accomplished by an adjusting nut 51 which is threadedly mounted upon the end of the head and engages with an outer casing 52 through which the head passes. The annular casing 52 serves to inclose the knife blade and actuating mechanism and is threadedly secured to a supporting ring 54 mounted upon the knife holder 46. The knife blade is connected to an adjusting ring 55 threadedly mounted upon the knife holder, as shown in Fig. 1, and by relatively rotating the knife holder and adjusting ring the blade may be moved axially. In order to conveniently perform this adjustment the adjusting ring is connected to the casing 52 by a pin 56 which is received in an elongated slot 70 formed in the casing, and thus by holding the casing and rotating the knife holder an adjustment of the blade is secured. The knife holder is rotated through a grooved drive pulley 57 which is mounted upon the holder and secured thereto by a clamping screw 58. The holder is mounted upon a hollow tapered support 59 journaled directly in the bearing 3 and connected to the holder 100

through a tapered sleeve 60, the support being adjusted endwise to hold the knife holder in its proper operative position relative to the bearing by a collar 61 which is 5 threadedly mounted upon the end of the support and engages with the opposite side of the bearing 3 from the drive pulley 57. With this construction it will be noted that a simple and compact mechanism has been 10 provided for adjusting the knife blade and for clamping it in any adjusted position and furthermore, the interior of the rotary knife is free and clear for the passage of chips or other waste material. The bearing 15 3 is provided with flanged projections 63 and 64 upon opposite sides secured to the casing of the machine and forming a substantial continuation of the hollow passage in the interior of the knife. The drive pulley 57 is actuated from a pulley 65 mounted upon the main drive shaft 40 of the machine and driven from any suitable source 20 by a main drive pulley 66.

It should be understood that it is within 25 the scope of the present invention to actuate either the upper or lower belt to feed the work and that the designation of the co-operating belts as feed members is for convenience of description, only.

30 While it is preferred to employ the specific construction and arrangement of parts shown and described, it will be understood that this construction and arrangement is not essential except so far as specified in 35 the claims, and may be changed or modified without departing from the broader features of the invention.

The invention having been described, what is claimed is:

40 1. A skiving machine, having in combination, a cylindrical skiving knife, feeding members having feeding surfaces engaging with opposite sides of the work to guide and feed the work to the knife and mechanism for adjusting the feeding surfaces to 45 determine the area of contact between the feeding surfaces and the work.

2. A skiving machine, having in combination, a cylindrical skiving knife, a pair 50 of co-operating feed belts engaging with opposite sides of the work to control the movements of the work relative to the knife, and mechanism for securing a relative adjustment of the feed belts to determine 55 the area of contact between the feeding surfaces and the work.

3. A skiving machine, having in combination, a cylindrical skiving knife, a pair 60 of feed belts engaging with opposite faces of the work to control the movements of the work relative to the knife, and mechanism for adjusting the belts angularly with relation to one another.

4. A skiving machine, having in combination, a cylindrical skiving knife, a feed

belt engaging with the under side of the work, a co-operating presser belt engaging with the upper side of the work, and mechanism for adjusting the presser belt angularly relative to the feed belt. 70

5. A skiving machine, having in combination, a cylindrical skiving knife, a feed belt, a presser belt, means for supporting the presser belt at opposite ends, and means for adjusting the presser belt angularly with 75 relation to the feed belt.

6. A skiving machine, having in combination, a cylindrical skiving knife, a pair of co-operating feed belts, mechanism for normally retaining the belts in a position 80 in which the working portions move in parallel paths, and means for securing a relative adjustment of the belts to cause the working portions to travel in paths inclined to one another. 85

7. A skiving machine, having in combination, a pair of co-operating feed members engaging with the work upon opposite sides of the cutting edge to determine the direction of feed of the work, a cylindrical skiving knife, and means for supporting the skiving knife at an inclination to the direction of feed of the work. 90

8. A skiving machine, having in combination, a cylindrical skiving knife having a 95 beveled outer surface, a pair of members including a belt engaging with opposite sides of the work to control the movements of the work relative to the knife, means for rotating the knife, and means for supporting 100 the knife at an angle to the direction of feed of the work.

9. A skiving machine, having in combination, a cylindrical skiving knife having a 105 passage extending entirely therethrough, a pair of co-operating members engaging with opposite sides of the work to control movements of the work relative to the knife, means for supporting the knife at an inclination to the direction of feed of the work, 110 and means for rotating the knife.

10. A skiving machine, having in combination, a knife holder, a knife blade supported externally of the holder, a clamping ring engaging with the outside of the knife 115 blade, means for contracting the ring to clamp the knife blade to the holder, and a pair of co-operating feed members including a belt for controlling the movements of the work relative to the knife. 120

11. A skiving machine comprising a cylindrical skiving knife, a head, a roll journaled in the head, an arm connected to the head and having a second roll journaled upon its free end, a belt supported at its 125 opposite ends upon the two rolls, and a curved arm adjustably connecting the free end of the roll supporting arm with the head.

12. A skiving machine, having in combi- 120

nation, a tubular skiving knife and a pair
of coöperating belts having feeding sur-
faces engaging with opposite sides of the
work to guide the work relative to the
5 knife, and means for supporting the belts
with their coöperating feed surfaces curved

substantially in conformity with the curva-
ture of the knife edge.
